UNITED STATES PATENT OFFICE.

SAMUEL F. PAUL, OF NEW YORK, N. Y.

DESIGN FOR A GLOVE-FASTENER.

SPECIFICATION forming part of Design No. 31,029, dated June 20, 1899.

Application filed May 26, 1899. Serial No. 718,445. Term of patent 14 years.

To all whom it may concern:

Be it known that I, SAMUEL F. PAUL, a citizen of the United States, residing in the city of New York, State of New York, have invented and produced a new and original Design for Glove-Fastenings, of which the following is a specification, reference being had to the accompanying drawings, forming a part thereof.

10 Figure 1 is a plan view of a glove-fastener, showing my new design. Fig. 2 is a side elevation of the same. Fig. 3 is a rear elevation of the same.

15 As shown in the drawings, the leading or material features of my design consist of a head containing a flat crown *a* and a down-

wardly-curved edge *b*, from one side of which head extends downwardly a corrugated neck *c*, from the lower portion of which neck extends forwardly and horizontally a base *d*, 20 from which *e* project downwardly, the front portion of the head overhanging beyond the front portion of the base *d*.

Having described my invention, what I claim as new, and desire to secure by Letters 25 Patent, is—

The design for glove-fastener, as herein shown and described.

SAMUEL F. PAUL.
